UNITED STATES PATENT OFFICE

121,620

DESIGN FOR A FIRE EXTINGUISHER OR SIMILAR ARTICLE

Harold V. Saffell, Los Angeles, Calif., assignor, by direct and mesne assignments, to Tetco Co.,
a corporation of California

Application July 3, 1939, Serial No. 85,823

Term of patent 14 years

To all whom it may concern:

Be it known that I, Harold V. Saffell, a citizen of the United States and residing at Los Angeles, in the county of Los Angeles and State of California, have invented a new, original, and ornamental Design for a Fire Extinguisher or Similar Article, of which the following is a specification, reference being had to the accompanying drawing, forming part thereof, in which:

Fig. 1 is a view in side elevation of the fire extinguisher or similar article showing my new design.

Fig. 2 is a front elevational view; and
Fig. 3 is an end view thereof.

I claim:

The ornamental design for a fire extinguisher or similar article, as shown.

HAROLD V. SAFFELL.
